UNITED STATES PATENT OFFICE.

PERKINS H. DE ROCHEMONT, OF CHATTANOOGA, TENNESSEE, ASSIGNOR
OF ONE-HALF TO CHARLES HERRON, OF CHATTANOOGA, TENNESSEE.

SINGLETREE END IRON.

SPECIFICATION forming part of Letters Patent No. 695,289, dated March 11, 1902.

Application filed October 26, 1901. Serial No. 80,098. (No model.)

To all whom it may concern:

Be it known that I, PERKINS H. DE ROCHEMONT, a citizen of the United States, residing at Chattanooga, in the county of Hamilton and State of Tennessee, have invented new and useful Improvements in Singletree End Irons, of which the following is a specification.

My invention relates to singletree end irons; 10 and its object is to provide a simple, inexpensive, and durable device of the character named which will serve as a trace hook or holder and effectually prevent the accidental disengagement of the trace therefrom.

15 The invention comprises a stationary member adapted to be secured to the end of a vehicle-singletree and a movable member or hook supported in position by the stationary member and serving as a guard or safety device to prevent the accidental disengagement 20 of the trace.

The construction and characteristic features of the invention will be specifically described in connection with the accompanying 25 drawings and its points of novelty set forth in the claims.

In the drawings, Figure 1 is a view in perspective of a singletree end iron or trace-holder embodying the invention applied to a 30 singletree. Fig. 2 is a top plan view of the same detached, and Fig. 3 is a view in perspective of the two members of the device separated.

The reference-numeral 1 designates an angle-plate, from the front of which projects an 35 integral hook 2. From the rear end of the plate 1 extends laterally an arm 3, having a curved offset 4, which forms a bearing 5, for the purpose hereinafter explained. The arm 40 3 is parallel to the front lateral arm 6 of the angle-plate, and both of said arms are formed with bolt-holes 7 to facilitate their attachment to a singletree 8. A spur or prong 9 projects from the inner side of the plate 1 45 and is designed to be driven into the end of the singletree to supplement the securing-bolt 10.

11 designates a hook constituting the movable member of the device and formed at its 50 rear end with a vertical elongated slot 12, the front wall 13 of which is beveled to adapt it

to conform to the outer rounded surface 14 of the curved offset of the arm 3, while its rear wall 15 is rounded to facilitate the movement of the hook.

55 As shown in the drawings, the hook 11 is supported within the seat or bearing 5 by passing the arm 3 through the slot 12 before the device is secured to the singletree.

The arms 3 and 6 embrace the end of the 60 singletree and are secured thereto by the means described, thus presenting the hook 2 in position to be engaged by the trace.

The rear slotted end of the hook 11 is inwardly curved, as at 16, to enable said hook 65 to snugly overlap the outer side of the rigid hook 2, and the front end of the hook 11 is formed with an inwardly-projecting lug 17, which closes the hook 2 and effectually prevents the disengagement of the trace without 70 the manipulation of the movable hook.

As shown in Fig. 1, the trace-ring engages both of the hooks 2 and 11 and is securely held thereby.

I claim—

75 1. A singletree end iron comprising a stationary member adapted to be secured to the end of a singletree and having a hook, and a movable member consisting of a hook having its rear end provided with a slot through 80 which the stationary member extends supported upon the stationary member and overlapping the hook thereof.

85 2. A singletree-iron comprising an angle-plate having a rigid hook projecting from the front thereof, and a laterally-extending arm at the rear curved to form a bearing, and a movable hook slotted at its rear end to receive the rear arm of the angle-plate and overlapping the outer side of the rigid hook.

90 3. The combination with the parallel arms, end plate and forwardly-projecting rigid hook, of a hook slotted and inwardly curved at its rear end and formed at its forward end with a lug to close the rigid hook.

95 4. A singletree-iron comprising an angle-plate formed with a bearing, a rigid hook projecting from the front end of the plate, and a movable hook slotted at its rear end to receive one arm of the angle-plate, whereby 100 said end is adapted to bear in the bearing.

5. A singletree-iron comprising an angle-

plate, a hook projecting from the front thereof, a laterally-extending arm, a prong formed thereon and projecting inwardly therefrom, a curved offset, and a movable hook having its rear end formed with an elongated slot adapted to receive one arm of the angle-plate, whereby said end is adapted to bear in the offset.

6. The combination with the angle-plate and forwardly-projecting rigid hook, of a mov-

able hook loosely mounted on the angle-plate and formed at its forward end with an inwardly-projecting lug to close the rigid hook.

In testimony whereof I affix my signature in presence of two witnesses.

PERKINS H. DE ROCHEMONT.
